(57) **CLAIM**

The ornamental design for a glove, as shown and described.

DESCRIPTION

The patent file contains at least one drawing executed in color. Copies of this patent with color drawings will be provided by the Office upon request and payment of the necessary fee.

FIG. 1 is a top perspective view of a glove showing our new design;

FIG. 2 is a top view thereof; and,

FIG. 3 is a bottom view thereof.

FIGS. 1-3 show a left hand glove. The right hand glove, which is not depicted in the drawings, is a mirror image of the left hand glove of FIGS. 1-3.
